SUSPENDERS

Lawrence E. Baer, Attleboro, Mass., assignor to
Swank Products, Inc., a corporation of Delaware

Application July 17, 1937, Serial No. 154,233

1 Claim. (Cl. 241—19)

This invention relates to suspenders or braces for supporting men's trousers; and the invention has for one of its objects the provision of suspenders which will be so connected in the back that they may lie flat and yet will be permitted a movement one with relation to the other.

Another object of the invention is the provision of a connection for adjusting the relative position of the straps which comprise the suspenders to accommodate the straps to different positions of the wearer, for more comfort to the wearer and less strain upon the straps than would otherwise be provided.

With these and other objects in view, the invention consists of certain novel features of construction, as will be more fully described, and particularly pointed out in the appended claim.

In the accompanying drawing:

Fig. 1 is a view of the back of the suspender straps incorporating the invention and shown as applied to a person indicated in dotted lines;

Fig. 2 is an enlarged fragmental view of the connection at the back of the straps showing my invention therein;

Fig. 3 is a view similar to Fig. 2 showing a different position of adjustment whereby one of the straps is raised with reference to the other and the different positions of the straps on the connection;

Fig. 4 is a perspective view of the connecting member;

Fig. 5 is a perspective view of one of the parts of the connecting member;

Fig. 6 is a section on line 6—6 of Fig. 4;

Fig. 7 is a sectional view showing the connection of one of the straps to one of the loop members.

In the use of suspenders it is desirable that the straps extend over the shoulders and connect to the back of the trousers by some arrangement to prevent them from spreading and at the same time permit a maximum amount of relative movement for comfort in wearing and for the preventing of unnecessary strains upon the straps; and in order to accomplish this object I have provided a pair of relatively rigid members which are connected in such a way that they will space the straps one from the other and yet are so pivoted that they will be rockable one on the other while the straps are connected to them in such a manner that they may slide about the loops of the members and thus a wide variety of adjustments may be accomplished; and the following is a more detailed description of the present embodiment of this invention, illustrating the

preferred means by which these advantageous results may be accomplished:

With reference to the drawing, 10 designates one shoulder strap and 11 the other shoulder strap, each of which is provided with some means to connect the front of the strap to the trousers, such means being of a common form and thought unnecessary to illustrate herein. Back straps 12 and 13 are connected to the back of the trousers 14 by any convenient means such for instance as 10 by the tabs 15 connected through buckles 16 to the back straps 12 and 13.

In order to connect the shoulder and back straps 10 and 12 on one side and the shoulder back straps 11 and 13 on the other side and yet 15 prevent the straps on one side from spreading with reference to the straps on the other side, I have provided a pair of loop members 18 and 19 which are preferably formed of some stiff or rigid material such for instance as metal, although 20 some other stiff and rigid material such as fiber may be employed. These loops are each provided with an ear or projection 20, which ears overlap each other, as shown in Fig. 4, while a pivot pin 21 extends through the openings 22 in each of 25 these ears to pivotally secure the loop members 18 and 19 together.

The lower end of the strap 10 and the upper end of the back strap 12 are slidably connected to the loop or ring 18 by means of tabs 23 and 24 30 each of which consists of a piece of leather passed through the ring 18 and folded upon itself at the narrow bight portion with one ply extending along one face of the strap and the other ply extending along the other face of the strap with stitching 35 25 sewing the two plies 26 and 27 of the tab together and also at the same time attaching the tab to the strap 10 or 12, as the case may be. Tabs 28 and 29 upon the straps 11 and 13 are of a similar shape and similarly attached to these 40 straps as are the tabs 23 and 24 to the straps 10 and 12.

Each of these tabs may slide freely around its ring or loop member and the ring members being pivoted one with relation to the other may rock 45 as one shoulder is raised and the other lowered so that the relative position of the straps may be either the normal arrangement as shown in Fig. 2 or the arrangement such as shown in Fig. 3 where the parts have changed their relative position both by the tab sliding around the rings and the straps 10 and 11 on one side being raised or relatively higher than the straps 11 and 13 on the other side. By this arrangement the parts are well supported and a maximum amount of 50 55

flexibility and relative change of position may be had and yet the arrangement is simple with the parts easily formed and easily adjusted and arranged.

5 The foregoing description is directed solely towards the construction illustrated, but I desire it to be understood that I reserve the privilege of resorting to all the mechanical changes to which the device is susceptible, the invention being defined and limited only by the terms of the appended claim.

I claim:

Suspenders comprising a pair of shoulder straps

having front ends provided with trouser engaging means, a pair of back straps provided at their lower ends with trouser engaging means, a pair of rigid metal rings, the back end of one shoulder strap and the upper end of one back strap being 5 slidably connected to one ring, and the back end of the other shoulder strap and the upper end of the other back strap being slidably connected to the other ring, lateral extensions on each ring overlapping, and a pivot pin extending through 10 said extensions.

LAWRENCE E. BAER.
